UNITED STATES PATENT OFFICE

170,016

CRADLE TELEPHONE LAMP

Robert Foss, Chicago, Ill.

Application February 12, 1953, Serial No. 23,584

Term of patent 14 years

(Cl. D48—20)

To all whom it may concern:

Be it known that I, Robert Foss, a citizen of the United States of America, residing at Chicago, in the county of Cook and State of Illinois, have invented a new, original, and ornamental Design for a Cradle Telephone Lamp, of which the following is a specification, reference being had to the accompanying drawing, forming part thereof.

Fig. 1 is a top plan view of a cradle telephone lamp, showing my new design;

Fig. 2 is a side elevational view thereof;

Fig. 3 is a front elevational view; and

Fig. 4 is a bottom plan view.

I claim:

The ornamental design for a cradle telephone lamp, as shown.

ROBERT FOSS.
